UNITED STATES PATENT OFFICE.

JOHN JACOB PATRICK BOATMAN, OF BLAINE, WASHINGTON.

GEARING.

No. 867,103.

Specification of Letters Patent.

Patented Sept. 24, 1907.

Application filed January 24, 1906, Serial No. 297,583. Renewed March 5, 1907. Serial No. 360,782.

To all whom it may concern:

Be it known that I, JOHN JACOB PATRICK BOATMAN, a citizen of the United States, and a resident of Blaine, in the county of Whatcom and State of Washington, 5 have invented certain new and useful Improvements in Gearing, of which the following is a specification.

My invention is an improvement in gearing and consists in certain novel constructions and combinations of parts described and claimed hereinafter.

10 Referring to the drawings forming a part hereof Figure 1 is a front elevation of a system of gearing provided with my improved cone. Fig. 2 is a longitudinal vertical section of the friction cone. Fig. 3 is a plan view of the larger flange removed. Fig. 4 is a 15 vertical longitudinal section of a cone constructed in the usual manner. Fig. 5 is a plan view of the removable flange thereof, and Fig. 6 is a perspective view of the sleeve showing the integral smaller flange.

In the practical application of my invention I provide 20 a sleeve A, having therein a key way a, and adapted to be secured to a shaft A', by means of a key a', engaging the key way in the sleeve, and a key way on the shaft. A flange B of relatively small diameter, is formed integral with one end of the sleeve, and is 25 provided with perforations b, for a purpose to be hereinafter described. A series of disks C, of paper or other suitable friction material, gradually increasing in diameter are arranged on the sleeve, and secured in place by a ring or flange D of relatively large diameter.

30 The flange or ring D is provided with a central opening for receiving the sleeve, and is retained in place upon the sleeve by a double gib or yoke key d engaging a key way d' in the flange, and a key way a' on the outer surface of the sleeve.

35 A series of bolts E, four in number, in the present instance, traverse the perforations in the smaller flange, aligned perforations in the friction disk, and perforations in the larger flange, and are engaged by nuts e on the face of the larger flange.

40 In Fig. 1 of the drawing is illustrated a system of gearing containing friction cones of my construction. In this figure, a vertical shaft F is provided at its lower end with a cone-faced wheel G and a horizontal shaft A' secured therebelow, supports the friction cone 45 for engagement by the cone-faced wheel.

In Fig. 3 is illustrated the friction cone as heretofore constructed, comprising a sleeve H, having integral with one end thereof a flange of relatively large diameter I, and removably secured to the inner end a flange 50 J of relatively small diameter. The friction disks are arranged between the flanges upon the sleeve and the removable parts secured by the bolts and nuts K.

55 In refilling the above described construction of cone, it is necessary to remove the supporting shaft from its bearings, the key attaching the sleeve to the shaft must be taken out, and all the parts including the sleeve re-

moved from the shaft. The smaller inside flange is itself removed from the sleeve by loosening the transverse bolts, and the friction papers or disks removed one by one, which is a very difficult operation. The 60 worn or useless disks are culled out and replaced by new disks enough to refill the cone. The parts are then re-assembled and the shaft returned to its bearings. Much time is required for this operation, it in ordinary cases requiring the services of two mill-wrights for approximately four hours, and in addition there is much wasted material, many of the disks being destroyed in removing them from the sleeve.

In refilling a friction cone of my construction it is only necessary to elevate one end of the shaft from its 70 bearings, remove it to one side of its hanger, and loosen the transverse bolts to slacken up the filling material. With a cold chisel worn or useless disks are cut away from the inside end of the cone and the remaining washers are shoved in against the inner flange. Enough 75 disks are then put upon the sleeve to replace those removed, the large flange is secured in place, and the shaft is returned to its bearings. Two mill-wrights can refill the worn cone of my construction in about one hour, and only the worn disks are destroyed.

80 It will be evident from the above that much time, labor and consequent expense is saved by the use of my improved cone, and that it will rarely be necessary to shut down the machinery for any considerable length of time on account of worn cones.

In Fig. 1, I have shown a mechanism whereby to easily adjust the cone on the shaft to compensate for wear. In this construction, a collar M provided with a set screw m whereby it may be fixed with respect to the shaft, is connected to the smaller disk B, by means 90 of the screw threaded rods m', secured to the disk, and traversing openings in the collar. Lock nuts m² are arranged upon the screw threaded rod upon each side of the collar, whereby to secure the cone in its adjusted position.

95 The collar may be of any desired construction, and after being placed on the shaft in proper position is fixed thereto by means of the set screw. When the cone becomes worn the lock nuts are loosened and the cone is adjusted, after which the lock nuts are again 100 tightened.

Having thus described my invention, what I claim as new and desire to secure by Letters Patent is—

1. In a friction cone gearing, the combination of the vertical shaft, a cone faced wheel secured to the shaft, a horizontal shaft journaled below the vertical shaft, a friction cone on the shaft and engaging the cone shaped face of the wheel, and comprising a sleeve mounted on the shaft, a key for securing the sleeve to the shaft, a flange of relatively small diameter integral with the sleeve at the inner end, a flange of relatively large diameter on the outer end of the sleeve, a yoke key engaging the flange and sleeve, friction disks of gradually increasing diameter from within outward on the sleeve between the flanges,

bolts traversing the aligned openings in the disks and flanges, and nuts on the outer face of the larger flange for engaging the bolts to secure the disks and flanges together.

2. In a friction cone gearing, the combination of a vertical shaft, a cone shaped wheel secured to the shaft, a horizontal shaft journaled below the vertical shaft, a friction cone on the shaft and engaging the cone shaped face of the wheel, and comprising a sleeve mounted on the shaft, a means for releasably securing the sleeve to the shaft, a flange of relatively small diameter integral with the sleeve at one end, a flange of relatively large diameter on the sleeve at its other end, means for securing the flange to the sleeve, friction disks on the sleeve between the flanges, and means for securing the friction disks and the flanges together.

3. In a friction cone gearing, the combination of the vertical shaft, a cone faced wheel secured to the shaft, a horizontal shaft journaled below the vertical shaft, a friction cone on the shaft and engaging the cone shaped face of the wheel, and comprising a sleeve arranged on the shaft, means for securing the sleeve to the shaft, a flange of relatively small diameter secured to the sleeve at its inner end, a flange of relatively large diameter removably secured to the outer end of the sleeve, friction disks on the sleeve between the flanges, and means for securing the disks and flanges together.

4. In a friction cone gearing, the combination of the vertical shaft, a cone faced wheel secured to the shaft, a horizontal shaft journaled below the vertical shaft, a friction cone on the shaft engaging the cone shaped face of the wheel, and comprising a sleeve mounted on the shaft, a flange of relatively small diameter rigid with the inner end of the sleeve, a flange of relatively large diameter re-

leasably secured to the outer end of the sleeve, friction disks on the sleeve between the flanges, and means for securing the flanges and disks together. 35

5. In a friction cone, the combination of a sleeve having an inner flange of relatively small diameter integral therewith, a flange of relatively large diameter movable thereon, and means for securing the flange to the sleeve comprising a yoke key seated in a groove on the sleeve, and having its arms embracing the faces of the flange. 40

6. A friction cone, comprising a sleeve having thereon a movable outer flange, and means for securing the flange to the sleeve comprising a double gib key resting in a groove 45 on the sleeve, and embracing the faces of the flange.

7. In a friction cone gearing, the combination of a vertical shaft, a cone faced wheel secured thereto, a horizontal shaft below the vertical shaft, a friction cone on the shaft engaging the cone shaped face of the wheel, and 50 means for adjusting the cone, comprising a collar loosely mounted on the shaft, a set screw for fixing the collar to the shaft, screw threaded rods secured to the cone and traversing openings in the collar and nuts on the rod on each side of the collar. 55

8. In a device of the character described, a shaft, a gear wheel on the shaft, and means for adjusting the gear wheel comprising a collar on the shaft, means for fixing the collar to the shaft, and means connecting the collar and the gear wheel whereby to adjust the wheel to and 60 from the collar.

JOHN JACOB PATRICK BOATMAN.
